C. W. LUMMIS.
REGULATING MECHANISM FOR GAS PRODUCERS.
APPLICATION FILED AUG. 5, 1918.

1,425,875.

Patented Aug. 15, 1922.

UNITED STATES PATENT OFFICE.

CHARLES W. LUMMIS, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

REGULATING MECHANISM FOR GAS PRODUCERS.

1,425,875.

Specification of Letters Patent. Patented Aug. 15, 1922.

Application filed August 5, 1918. Serial No. 248,477.

To all whom it may concern:

Be it known that I, CHARLES W. LUMMIS, a citizen of the United States, residing at Worcester, in the county of Worcester and Commonwealth of Massachusetts, have invented a new and useful Improvement in a Regulating Mechanism for Gas Producers, of which the following, taken in connection with the accompanying drawings, is a specification.

The present invention relates to the regulation of gas producers, for the purpose of obtaining the production of gas thereby in direct proportion to the fluctuations in the demands of the gas-consuming agencies.

In systems involving the supply of producer gas for metallurgical or other operations, from one or more gas producers, the present invention contemplates the regulation of the producer or producers in such a manner as to make the rate of gas production substantially equal to the rate of gas consumption; in other words, when the demand for gas in the system is either increased or diminished, the rate of gas production is correspondingly changed, thereby causing the system to operate at the maximum efficiency, and avoiding at all times both an under supply or an over supply of the gas.

The above and other objects are attained by the employment of automatic mechanism operable on the agencies of the gas producer or producers which directly affect the rate of gas production, namely the fuel and blast supply devices. The rates of fuel and blast supply for the production of gas are made directly responsive to the rate of gas consumption in the system, so that when more gas is being used, an increase in the rate of production is obtained, and vice versa, when the demand for gas decreases, the production is correspondingly lessened. One form of the invention is set forth and described hereinafter, reference being had to the accompanying drawing, the single figure of which is a diagrammatic representation of so much of a producer gas supply system as is necessary to show the invention.

Referring to the accompanying drawing 1 denotes a gas producer of conventional construction, which, if desired, may be in-

cluded in the battery of similar devices, all having their interior chambers 2 connected to a common gas main 13, by means of suitable flues, not shown, that are led from their outlet openings 14. Each producer of a battery, only one being shown, is provided with a rotary feeding mechanism 3, which in the present instance is substantially like that covered by United States Patent No. 1,270,963, issued to me July 2, 1918. An intermittent rotary motion is imparted to an oscillating bell crank 4, one arm of which is pivotally connected by a link 5 with a slide 6, capable of a radial movement on an oscillating arm 7. The arm 7 is carried by a shaft 8 journaled in a support 9 and provided with an arm 10, which is pivotally connected by a link 11 with an actuating crank disk 12. The amplitude of movement of the oscillating bell crank 4 will be increased or diminished by the radial position of the slide 6 on the oscillating arm 7. By moving the slide 6 toward the free end of the arm 7 the swinging movement of the bell crank 4 will be increased, with a resultant increase in the amount of fuel fed to the gas producer. The movement of the slide 6 on the arm 7 toward the shaft 8 will diminish the movement of the bell crank 4 and lessen the rate of fuel feeding. By the employment of certain instrumentalities, the position of the slide 6 on the arm 7 is controlled and determined in accordance with the rate of use of the gas flowing through main 13, and hence, the rate of fuel supply to each of the producers of the battery, or to the producer 1 as the case may be, is made responsive to the rate of use of gas, as hereinafter described.

According to the invention, the supply of gas in the main 13, which is common to all of the producers of the battery, is drawn upon by all of the gas consuming agencies, furnaces or the like, of the system. In consequence of this, the fluctuations in the quantity of gas consumed, due to the variations of demand of the gas using agencies, are communicated directly to the main 13, and according to the invention these fluctuations in the main 13 are in turn communicated to the gas producer or producers in order to vary the rate of gas making. To this end, the main 13 is equipped with a suitable de-

vice adapted to move in response to the fluctuations of the gas supply therein; such a device is here shown by way of example as a water sealed gas bell 15 of ordinary construction disposed in surrounding relation to an opening 16 in the main. The bell 15 is connected by a link 17 with a lever 18, pivoted at one end to a fixed bracket 19 said lever carrying at one end a weight 18^a which substantially counterbalances the weight of bell 15.

When the rate of gas consumption in the system is substantially constant, and equal to the rate of production, the bell 15 is stationary, as will be well understood. When the rate of consumption is increased over the rate of production, the gas contained in the bell 15 flows into the main 13 to make up for the discrepancy which would otherwise occur and consequently the bell is lowered. Conversely, if the consumption be decreased, the excess gas flows into the bell and raises it. The movement of the bell thus serves to indicate the relation between the rates of consumption and production, rising when the production is greater than the consumption and lowering when the consumption exceeds the production.

If these movements be communicated to the gas producing agencies of the gas system, increasing the quantity of blast and fuel as the bell descends and decreasing it as it rises, it is evident the rate of gas production may be made to follow the varying demands of the gas-consuming agencies. It is also evident that when so connected to the gas-producing means, the delicately balanced bell will maintain a constant pressure of gas in the main just sufficient to balance any weight of the bell and levers in excess of the counterbalance weight 18^a.

It is evident that the small force exerted by lever 18, connected to bell 15, is not, under ordinary circumstances, sufficient to shift the slide 6 inwardly and outwardly on the arm 7, so as to vary the rate of fuel supply to the producers. It becomes necessary therefore to introduce between the lever 18 and the fuel supply controlling devices, a suitable actuating device for the latter, said actuating device being regulated and controlled by the movement of the lever 18. Any suitable power actuated mechanism for this purpose will suffice; in the present instance, there is shown a reversible electric motor arranged to impart movement to the slide 6 on arm 7, and the operation of this motor is under the control of the lever 18, as hereinafter described.

Secured to the lever 18 is a downwardly extending link 20, having an insulated head 21 to which are secured contact members or brushes 22 and 23. The brushes 22 and 23 are connected by wires 24 and 25 with a source of electricity. Supported in a frame

26 are four insulated contact plates 27, 28, 29 and 30, each connected by suitable wiring with a reversible motor 31. The motor 31 is operatively connected through a motor shaft 32 with a crank shaft 33 journalled in a supporting bracket 34 and carrying on one end a crank arm 35. The free end of the crank arm 35 is pivotally connected by means of a link 36 with the link 5. The link 36 is provided with a turnbuckle 36^a for the manual adjustment of the length of the link and the initial adjustment of the slide 6. A lever 37, pivoted to a fixed bracket 38, has one end slotted, as at 37^a, for connection to the rod or link 36. The opposite end of the lever 37 is pivoted to a rod 39 upon which the frame 26 is mounted. The brushes or contacts 22 and 23 are slightly shorter than the space between the upper pair of contacts 29 and 30 and the lower pair of contacts 27 and 28, so that in the normal operation of the system said brushes 22 and 23 are in a neutral position, the motor 31 being thereby inoperative.

When the rate of gas consumption increases, the consequent lowering of bell 15 and link 20 will cause the brushes 22 and 23 to make contact with the plates 27 and 28, thereby inaugurating the operation of the motor 31 in a direction to produce clockwise rotation of crank arm 35, thus raising the slide 6 on the arm 7 so as to increase the throw of bell crank 4 and thus speed up the feeding of fuel to the producer. The rotation of the motor 31 above described is only momentary, for immediately the frame 26 is lowered through lever 37 and rod 39 to destroy the contact between the brushes 22 and 23 and the plates 27 and 28; however, the new position assumed by the crank arm 35 assures the maintenance of the increased rate of feeding until there is another change in the demand for gas. Simultaneously with this increased rate of feeding fuel the blast of air and steam to the producers is increased in volume by any suitable mechanism responsive to the movement of lever 18. As herein shown, the link 20 has adjustably connected thereto a lever 40, which is pivoted on a bracket 41 carried by valve 115 casing 42. Steam passes through pipe 43 into said valve casing and thence is led through pipe 44 to a suitable blower for inducing air with it into the producer, the blower being proportioned to induce a quantity of air substantially proportionate to the quantity of steam flowing. A valve, not shown, within said casing is provided to throttle the steam, and the stem 45 of this valve is connected to the lever 40. In this way, when the rate of fuel feeding is increased by the lowering of link 20, as above described, the rate of admitting blast to the producers is correspondingly increased, as will be well understood.

- When, in the operation of the system, there occurs a decrease in the rate of consumption, the consequent surplusage of gas in the main 13 brings about an immediate 5 elevation of the bell 15, and this causes the brushes 22 and 23 to contact with the plates 29 and 30. In this position of the electrical control devices, the motor 31 is started up and runs in such a direction as to produce 10 counter-clockwise rotation of crank arm 35, thereby lowering the slide 6 on the arm 7 and decreasing the throw of the bell crank 4, so as to produce a lower rate of fuel feed. Simultaneously with this adjustment, the 15 valve stem 45 is moved downwardly to throttle the steam to the producers, so as to obtain a rate of gas production substantially in accordance with the lowered rate of gas consumption. As before, the motor 20 31, after accomplishing the regulation of the fuel supply, comes to a stop because the frame 26 is moved upwardly to carry the contacts 29 and 30 away from the brushes 22 and 23. It will be seen that the mechanism 25 above described readily adjusts itself to each variation in the rate of gas consumption that may occur, and acts on the fuel feeding and blast instrumentalities of the system in such a manner as to maintain 30 the rate of gas production substantially equal at all times to the demand. In this way the system is able to respond almost instantaneously to a sudden increase or decrease in the demand for gas.
- 35 I claim,
1. In a gas supply system, the combination with a member movable in response to fluctuations in the demand for gas, of means controlled by the movement of said member for increasing or decreasing the rate of 40 supplying fuel for gasification to said system.
  2. In apparatus of the class described, the combination with gas producing and gas consuming agencies, of a member movable 45 in response to fluctuations in the demand of said gas consuming agencies, and means controlled by the movement of said member for changing the rate of supplying fuel to said gas producing agencies.
  3. In a gas supply system, the combination with a member movable in response to fluctuations in the demand for gas, of mechanical means for continuously feeding fuel for gasification to said system, and 50 means set in action by the movement of said member for changing the rate of operation of said fuel feeding means.
  4. In a gas supply system, the combination with mechanical means for continuously 55 feeding fuel for gasification in said system, of means responsive to fluctuations in the demand on the system for gas, for changing the rate of operation of said fuel feeding means.
  - 60 5. In apparatus of the class described, the combination with gas producing and gas consuming agencies, of a member movable in response to fluctuations in the demand of said gas consuming agencies, continuously operating fuel feeding means for said gas 65 producing agencies, and means controlled by the movement of said member for changing the rate of operation of said fuel feeding means.
  6. In a gas supply system, means for continuously supplying fuel for gasification, means operable to vary the rate of fuel supply, and means, responsive to fluctuations in the demand for gas in the system, for inaugurating the action of said last mentioned means.
  7. In apparatus of the class described, the combination with gas producer fuel feeding means for continuously supplying fuel for gasification, of force applying means 80 operable to vary the rate of fuel supply, and means for controlling said force applying means in response to fluctuations in the demand for gas.
  8. In apparatus of the class described, the combination with gas producing and gas consuming agencies, of means for continuously supplying fuel for gasification by said producing agencies, a motor operable to change the rate of fuel supply, and means, 85 responsive to fluctuations in the demand of said gas consuming agencies, for inaugurating the action of said motor.
  9. In apparatus of the class described, the combination with gas producing and gas consuming agencies, of means for continuously supplying fuel for gasification by said producing agencies, a motor operable to change the rate of fuel supply, and means, 90 responsive to fluctuations in the demand of said gas consuming agencies, for inaugurating the action of said motor in one direction to increase the rate of fuel feeding, and in the other direction to decrease the rate of fuel feeding.
  10. In apparatus of the class described, the combination with gas producing and gas consuming agencies, of means for continuously supplying fuel for gasification by said producing agencies, a motor operable 100 to change the rate of fuel supply, means responsive to fluctuations in the demand of said gas consuming agencies for inaugurating the action of said motor in one direction to increase the rate of fuel feeding, and in the other direction to decrease the rate of fuel feeding.
  11. In apparatus of the class described, the combination with gas producing and gas consuming agencies, of means for continuously supplying fuel for gasification by said producing agencies, a motor operable 110 to change the rate of fuel supply, means responsive to fluctuations in the demand of said gas consuming agencies for inaugurating the action of said motor, and means responsive to the operation of said motor for procuring the stoppage thereof.
  12. In apparatus of the class described, the combination with gas producing and gas consuming agencies, of means for continuously supplying fuel for gasification by said producing agencies, a motor operable 115 to change the rate of fuel supply, means responsive to fluctuations in the demand of said gas consuming agencies for inaugurating the action of said motor, and means responsive to the operation of said motor for 120 procuring the stoppage thereof.
  13. In apparatus of the class described, the combination with gas producing and gas consuming agencies, of means for continuously supplying fuel for gasification by said producing agencies, a motor operable 125 to change the rate of fuel supply, means, responsive to fluctuations in the demand of said gas consuming agencies, for inaugurating the action of said motor in one direction to increase the rate of fuel feeding, and in the other direction to decrease the rate of fuel feeding.
  14. In apparatus of the class described, the combination with gas producing and gas consuming agencies, of means for continuously supplying fuel for gasification by said producing agencies, a motor operable to change the rate of fuel supply, means, responsive to fluctuations in the demand of said gas consuming agencies, for inaugurating the action of said motor in one direction to increase the rate of fuel feeding, and in the other direction to decrease the rate of fuel feeding.
  15. In apparatus of the class described, the combination with gas producing and gas consuming agencies, of means for continuously supplying fuel for gasification by said producing agencies, a motor operable to change the rate of fuel supply, means, responsive to fluctuations in the demand of said gas consuming agencies, for inaugurating the action of said motor in one direction to increase the rate of fuel feeding, and in the other direction to decrease the rate of fuel feeding.

tion to increase the rate of fuel feeding, and in the other direction to decrease the rate of fuel feeding, and means responsive to the operation of the motor in either direction for procuring the stoppage thereof.

12. In apparatus of the class described, the combination with gas producer fuel feeding means for continuously supplying fuel for gasification, of a member movable in response to fluctuations in the demand for gas, and force applying means interposed between said member and said feeding means, for procuring the adjustment of the latter in proportion to the demand for gas.
13. In apparatus of the class described, the combination with gas producer fuel feeding means for continuously supplying fuel for gasification, said means being adjustable to vary the rate of fuel supply, and force applying means, set in operation by

fluctuations in the demand for gas, for procuring the adjustment of said fuel feeding means.

14. In apparatus of the class described, the combination with gas producing and gas consuming agencies, of means responsive to fluctuations in the demands of said gas consuming agencies for regulating the supply of blast to said gas producing agencies, fuel feeding means for continuously supplying fuel to said gas producing agencies, and means for procuring the adjustment of said last named means in accordance with the quantity of blast supplied.

Dated this 29th day of July 1918.

CHARLES W. LUMMIS.
